UNITED STATES PATENT OFFICE

148,098

DESIGN FOR AN ELECTRIC LIGHT SUPPORT

Emanuel Tanchuck, Los Angeles, Calif.

Application January 30, 1946, Serial No. 126,109

Term of patent 3½ years

(Cl. D43—20)

To all whom it may concern:

Be it known that I, Emanuel Tanchuck, a citizen of the United States, residing at Los Angeles, in the county of Los Angeles and State of California, have invented a new, original and ornamental Design for Electric Light Support, of which the following is a specification, reference being had to the accompanying drawing, forming part thereof.

The drawing illustrates an electric light support embodying my new design in which Fig. 1 is a perspective view, Fig. 2 is a side elevational view, Fig. 3 is a top plan view, and Fig. 4 is an end elevational view.

In Fig. 1, an electric lamp socket mounted on

the support is shown in dotted lines for illustrative purposes only.

I claim:

The ornamental design for an electric light support, as shown and described.

EMANUEL TANCHUCK.
